UNITED STATES PATENT OFFICE.

CHARLES FRED SCHMITZ, OF GLENSIDE, PENNSYLVANIA.

HAIR-WAVING DEVICE.

Application filed July 28, 1925. Serial No. 46,512.

My invention relates to improvements in a hair waving device for producing what is known as a permanent wave. The object of my invention is to provide a waving device in which the weight is greatly reduced and in which the size is also produced, relatively to those now in use; a further object of my invention is to embody the electric heating element within the core member 5 upon which the hair is wound instead of surrounding the coil of hair with a sleeve having a heating element therein, as is now the practice; a still further object of my invention is to provide a core containing the 10 electric heating element with a detachable cable connector upon one end thereof and to construct said parts sufficiently small in diameter that the paper or fiber protecting tube, now used for encasing the coil of hair 15 may be readily slipped over the end of the core carrying one member of the cable connector and thus avoid the necessity of using a tube which is any larger in diameter than those now in use; and a still further object 20 of my invention is to provide a novel method of waving hair by which better results and more permanent waving is obtained.

Permanent hair waving machines such as now in general use employ a large number 30 of waving devices for the separate strands of hair, therefore any reduction in the weight and size of the separate waving devices is of great advantage and an advancement in the art.

Referring to the accompanying drawings: Fig. 1, is a view in elevation of my improved waving device showing a coil of hair thereon and showing the heat retaining tube surrounding the hair, said tube being shown 35 in section; Fig. 2 is an enlarged transverse section on line 2—2, Fig. 1; Fig. 3, is an enlarged longitudinal sectional view of the core containing a heating element and showing one member of a cable connector secured 40 upon said core, and Fig. 4, is a view in elevation of the heat retaining tube drawn on the same scale as Fig. 3, showing that said tube may be passed over the connector and core.

Referring to the drawing in which like reference characters refer to like parts, 5 represents the core of the hair waving device which is of hollow construction and preferably consists of a metal tube. At one 55 end of the core 5 is formed, or secured, a fastening device 6, having a cord retaining

slot 7 formed therein, similar in construction to those now in use upon the solid core rods upon which the hair is wound.

An electric heating unit 8, of any well known type, is mounted within the core 5 and is adapted for heating the core 5 throughout its entire length. Upon the opposite end of the core 5 from that at which the fastening device 6 is located, is secured 60 the member 10 of a cable connector having a counter part 12 with which it may be readily attached and detached. The connector member 10 is provided with contact pins 13 and 14 which are electrically connected with 65 the heating unit 8 in the usual manner. The connector member 12 is adapted to receive the pins 13 and 14 and complete the electric circuit from the cable or wires 16, with the 70 heating unit 8.

A tube 20 of fiber and asbestos or any other heat retaining material is provided for encasing the coil of hair and said connector member 10 is of sufficiently small diameter that the tube 20 will readily pass 75 over said member 10, when it is detached from the member 12.

The core 5 is covered with a fabric 22, consisting preferably of a sheet of flannel prepared in the usual manner with borax 80 and oil as now generally used in connection with hair waving devices.

The operation of my novel hair waving device is as follows: a cord 25 is tied around a strand of hair 30, close to the scalp, as 85 shown in Fig. 1, and the cord is secured in the notch 7 formed in the fastening device 6. The strand of hair 30 is tightly coiled around the core 6, having the fabric 22 thereon, and the outer end of the strand 30 is 90 secured by several turns 26 of said cord 25. The retaining tube 20 is passed over the connector member 10 and over the coil of hair, as shown in Fig. 1. The connector members 10 and 12 are attached so as to complete the 95 circuit including the heating unit 8.

By locating the heating unit in the core 5 around which the strand of hair is wound, I provide a method by which the hair may be more tightly wound around the fabric 22 and 100 by locating the heating unit within the fabric and coil of hair, the heat must pass through the fabric to the coil of hair. The tube 20, which is located outside of the heating unit, retains the heat around the coil 110 of hair, thus producing a more effective waving of the hair than has been heretofore

obtained in hair waving devices, in which the heating unit is located around the outside surface of the tube containing the hair; the latter being wound around a center core 5 which is not heated. The unheated metal core tends to draw the heat out of the coil of hair, whereas in my novel method the heated core drives the heat through the hair from the center of the coil outwardly and 10 the heat retaining tube encases both the coil of hair and the heating unit.

I claim:

1. A device for heating a coil of hair in the practice of permanent hair waving, comprising a tube for containing the coil of hair, a core, a layer of hair waving material immediately surrounding the core around which the hair is coiled and an electric heating unit within said core.
- 20 2. A device for heating a coil of hair in the practice of permanent hair waving, comprising a tube for containing the coil of hair, a rigid core, a layer of absorbent material surrounding the core around which layer 25 the hair is coiled, and an electric heating unit within said core.
3. In a device of the character described,

a core adapted to have a strand of hair coiled thereon having means at one end of said core adapted to be secured to the strand 30 of hair adjacent to the scalp, an electric heating unit in said core, a heat retaining tube adapted to encase the coil of hair when wrapped around said core, a connector member adapted for detachably connecting electric conductors to said heating unit located at the opposite end of said core, and said tube whereby said tube may be passed over 35 said member after the hair is coiled upon the core.

4. The method of waving hair comprising coiling the hair around a heating core covered with a permanent hair waving layer of chemically prepared fibrous material, enclosing the coil of hair in a heat retaining tube, and applying the heat to said core for producing heat within the fibrous material thereby forcing the chemically saturated moisture outwardly from said fibrous material through the coil of hair.

In testimony whereof I affix my signature.

CHARLES FRED SCHMITZ.
